UNITED STATES PATENT OFFICE

CLARA F. LOWRY, OF DASSEL, MINNESOTA

BOOKHOLDER AND TABLE

Application filed February 16, 1928. Serial No. 254,789.

My invention relates to a new and useful device which is a combination book holder and table particularly adaptable for use in homes, libraries, hospitals or any place where a person wishes to have a number of books open before him and other books readily available.

My device includes a novel, collapsible and disappearing book holding device adapted to be dropped into the table pedestal and a 10 slidable table top, for purposes hereinafter fully described and as illustrated in the accompanying drawing, in which,

Fig. 1 is a perspective view of my improved device in position to be used for holding one or more books in readable position.

Fig. 2 is a side elevation of my device with its top in offset position, and the book-holding frame or rack folded up and being inserted in the hollow pedestal.

Fig. 3 is an enlarged view of the upper part of Fig. 2 looking toward the latter as from the right.

Fig. 4 is an enlarged top view of the pedestal and the book holding frame in horizontal position and projecting from the said pedestal.

Referring to the drawing by reference numerals, 5 and 6 designate respectively a 30 preferably circular base or foot piece and a tubular column fixed in and extending vertically from the center of said base. The top of column 6 is cut off horizontally and has affixed to it a table top supporting plate 7 with parallel, integral and upwardly offset flanges edges 7F. The plate 7 has a circular aperture 7A somewhat smaller than the inner diameter of the column 6 (see Fig. 4) and concentric thereof, and 7A' is a notch from 35 one side of said aperture for inserting or removing a bar 12 hereinafter fully described.

8 is a table top of suitable material and size, preferably about nine inches wide by 45 twenty inches long and on the under side of which is secured transversely as at 9 two parallel rails 10 to slidably engage the flanges 7F of plate 7. Thus the top 8 may be positioned centrally over the column or moved 50 out sideways to clear the opening 7A as in

Fig. 1. The table top is of course useful in either position, but when it is in offset position a certain rack device presently to be described is accessible in the opening 7A and can be pulled out to horizontal position and set up for holding open books in readable position near the column and in spaced relation to the said top. Said rack comprises an elongated U-shaped main frame made of a single piece of round bar 11 the closed end of which is bent at an angle with relation to the parallel arms of said frame and on said angular part is fixed a cross member 12 of flat bar material and of a length slightly less than the inside diameter of column 5. Said bar has upwardly directed shoulders 11S at its opposite ends to engage the diametrically opposite edges of plate 7 in its aperture 7A while the loop end of frame 11 as 11L in Fig. 4 engages under the circular flange formed in plate 7 between its aperture 7 and the column 5, simultaneously as the bar 12 engages the edges of the aperture 7A and the horizontal parts of the bars 11 rest on plate 7 and project outwardly therefrom. 75 On said parts of bars 11, exteriorly of plate 7, I provide an elongated sheet metal hook support 13 of Z-shape in cross section, one flange of which is beaded to one of the parallel bars 11 and the other flange bearing 80 against and suitably secured to the near side of the adjacent bar 11 and said support 13 extending the length of said bars and a cross member 14 reenforcing the outer extremity of the rack and having preferably a notch 14N 85 to serve as a finger hold or catch (see Fig. 1). The web of said support is in a downwardly and rearwardly directed plane and designated as 13W in Fig. 1; 13F is the rear flange and 13F' the front flange beaded around the front bar 11. The web 13W serves as a rest for the bottom edge of a number of books, open or closed, and I have further provided back rests to hold said books up in inclined position. Said back rests for the books comprises a number of upright bars 15 the lower ends of which are pivoted to flange 13F and an end upright 15A held upright in a pocket 16 resembling a stake pocket and fixed to 13F 95 near the member 14. The upper ends of the 100

members 15—15A are all connected pivotally by a sectional bar 17. Said uprights 15—15A and bars 17 being all in a common rearwardly inclined plane it is obvious that they serve as back rests for books placed on the ledge 13W.

18 are auxiliary book or pamphlet holding means comprising pairs of metal bars pivotally secured in pairs to bar 17 as at 19 and said pairs of bars in spaced relation to each other. Each said pair of bars it will be readily understood are one bar on each side of bar 17 and both adapted to be swung to upright position and as they are preferably made of spring bar stock it is obvious that they are readily adapted for holding a booklet, pamphlet or the like, designated 20, in upright plane and above the books (not shown) supported on 13W and propped up by the bracket member 15—17.

21 is a row of upwardly directed projections in the upper front part of web 13W, preferably struck up of the metal therein and serving as obstructions to prevent leaves of an open book on the back from springing outwardly.

The entire book-holding rack is readily collapsed as follows:

First, prop 15A is withdrawn upwardly from the pocket 16, then it (15A) and its adjoining bar 17 are folded together and parallel to the next section of bar 17 after which these members are swung down with props 15 to lie flat within the angle of flange 13F and web 13W (see A in Fig. 4). Then the operator grasps the bar 14 and raises the entire (folded) book holding rack to vertical position (see Fig. 2) concentric over aperture 7A and lowers it into the column. The rack should of course be of such dimensions and proportions that (when folded) it will readily slide down into the tubular column and come to rest with the finger hold bar 14 accessible in the aperture 7A. With the book rack thus placed out of the way the board 8 can be moved over to position concentrically over the column 5 completely covering the plate 7. It will further be readily understood that the book rack of my device may be swung to various angles, in a horizontal plane, while resting on plate 7 and said variable positions being limited only by the size of said plate 7.

The use of my device has been fully revealed in the foregoing description. It might be stated further, however, that it has a multiplicity of uses, particularly as stated, in homes, libraries and hospitals and in the latter places may be used as a combination meal-tray holder and reading rack. Variations in construction may also be incorporated without departing from the scope and spirit of the invention.

I claim:

1. In a reading stand of the class described, a suitable base, a tubular column mounted

vertically on said base, a horizontal two-rail plate fixed on top of said column and having an aperture over the top opening of said column but smaller than said latter opening, a table top mounted to be slidably guided in horizontal plane on said rail-plate, a book holding rack adapted to be retained in said hollow column and to be slidably removable therefrom, and means for holding said rack with its base in horizontal position and outwardly from the column, and collapsible book supporting and resting means on said rack.

2. The structure specified in claim 1 in which said book holding rack comprises an elongated U-shaped frame support an elongated base plate on said U-frame and of approximately Z-shape in cross section, said means for holding the book rack horizontally comprising a cross member fixed on the arms of said U-frame near its closed end and said member having at each end a shoulder to engage the metal of the rail plate underneath its aperture when the adjacent parts of the U-frame outwardly thereof rest on the rail plate and the rack member extends simultaneously outwardly and horizontally therefrom.

3. The structure specified in claim 1 in which said book holding rack comprises an elongated U-shaped frame support, an elongated base plate on said U-frame and of approximately Z-shape in cross section, said means for holding the book rack horizontally comprising a cross member fixed on the arms of said U-frame near its closed end and said member having at each end a shoulder to engage the metal of the rail plate underneath its aperture when the adjacent parts of the U-frame outwardly thereof rest on the rail plate and the balance of the rack member extends simultaneously outwardly and horizontally therefrom, said collapsible book rest means comprising a series of pivotally connected bars, a number of said bars pivotally connected to an upright flange of said base plate, said bars arranged to be swung upwardly in a common plane or folded downwardly selectively to folded position within the base plate, and finger engaging means on the outer end of said rack.

4. The structure specified in claim 1 in which said collapsible means providing a book rest, comprises a quadrangular frame of pivotally connected bars also pivotally connected to the base of the rack to be swung into operative position upwardly from said plate, in an inclined plane and further rest means comprising pairs of flat bars pivotally fixed to the uppermost bars of said quadrangular frame and arranged to be extended upwardly from said frame in pairs, for the purpose set forth.

In testimony whereof I affix my signature.
CLARA F. LOWRY.
